CLAIM

The ornamental design for a blood-pressure cuff, as shown and described.

DESCRIPTION

FIG. 1 is a top perspective view of the portions of the blood-pressure cuff according to an embodiment of the present invention;

FIG. 2 is a bottom perspective view of the portions of the blood-pressure cuff shown in FIG. 1;

FIG. 3 is a top view of the portions of the blood-pressure cuff shown in FIG. 1;

FIG. 4 is a bottom view of the portions of the blood-pressure cuff shown in FIG. 1;

FIG. 5 is a side view of the portions of the blood-pressure cuff shown in FIG. 1;

FIG. 6 is a front-end view of the portions of the blood-pressure cuff shown in FIG. 1; and,

FIG. 7 is a rear-end view of the portions of the blood-pressure cuff shown in FIG. 1.

The broken lines in the figure views are included for the purpose of illustrating portions of the blood-pressure cuff that form no part of the claimed design.
